LENS SURFACING MACHINE

Joseph J. McCabe, Rochester, and George C. Schelling, Irondequoit, N. Y., assignors to Bausch & Lomb Optical Company, Rochester, N. Y., a corporation of New York

Application January 11, 1937, Serial No. 119,920

6 Claims. (Cl. 51—160)

The present invention relates to lens surfacing machines and more particularly to lens surfacing machines capable of forming spherical, cylindrical, toric or other surfaces on a lens.

One of the objects of the present invention is to provide a new and improved lens surfacing machine capable of forming spherical, cylindrical, toric or other surfaces on a lens. Another object is to provide a lens surfacing machine having an improved mechanism for regulating the pressure between the lens and lap. A further object is to provide a new and improved clamp for holding the grinding lap in a lens surfacing machine. Still another object is to provide a lens surfacing machine having means for protecting the internal mechanism from abrasives. These and other objects and advantages reside in certain novel features of construction, arrangement and combination of parts as will hereinafter be more fully set forth and pointed out in the appended claims.

Referring to the drawings:

Fig. 1 is a front elevation of a lens surfacing machine embodying our invention.

Fig. 2 is a top plan view thereof.

Fig. 3 is a top view with the upper portion of the housing removed to show interior structure.

Fig. 4 is a front view with the front wall removed and parts in section.

Fig. 5 is a section taken on line 5—5 of Fig. 4.

Fig. 6 is a section taken on line 6—6 of Fig. 4.

Fig. 7 is a section taken on line 7—7 of Fig. 4.

Fig. 8 is a section taken on line 8—8 of Fig. 3.

Fig. 9 is a section taken on line 9—9 of Fig. 8.

Fig. 10 is a section taken on line 10—10 of Fig. 3.

Fig. 11 is a section taken on line 11—11 of Fig. 10.

Fig. 12 is a section taken on line 12—12 of Fig. 5.

A preferred embodiment of the present invention is illustrated in the drawings wherein 20 indicates generally the housing of a lens surfacing machine having an upper section 21 and a lower section 22 secured together as by bolts 23. A removable door 24 having a knob 25 is provided in the upper section 21 to permit easy access to the interior of the housing 20.

Secured to the front wall of the lower section 50 22 of the housing 20 by bolts 26 is a support 27 having on its upper surface a fixed jaw 28 and a positioning key 29. A bearing member 30 having a spherical head 31 is secured in the lower front part of the support 27 and a movable jaw 32 is 55 provided with a conical recess 33 for engaging the

spherical head 31. A screw 34 provided with a hand grip 35, extends through an opening 36 in the movable jaw 32 and is threaded into the support 27. In order to prevent emery or other abrasive from getting on the screw 34 or bearing head 31, an overhanging skirt 37 is formed on the support 27 and two similar skirts 38 are formed on the movable jaw 32. The lap 39 is formed with a recess 40 in its lower surface to engage the positioning key 29 and, when the screw 10 34 is tightened, the face of the hand grip 35 bears against a projection 41 on the movable jaw 32 and moves this jaw to clamp the lap 39 in position.

As best shown in Figs. 3, 8 and 9, a shaft 42 15 extends through a bushing 43 on one of the side walls of the lower section 22 of the housing and is journaled in a bearing formed in a projection 44 on the rear wall of the lower section 22. This shaft 42 is driven from a source of power, not shown, by means of the pulley 45. A yoke 46 is fixed on the inner end of the shaft 42 by means of a key 47 and set screw 48. A stub shaft 49 is journaled in the yoke 46 with its axis parallel to the axis of the shaft 42 and can be locked in position by a set screw 50 which is threaded transversely through the shaft 49 and extends outward through a linear slot 51 in the yoke 46. A plate 52 is fixedly secured on the stub shaft 49 30 and carries a second stub shaft 53 parallel to the stub shaft 49. It can be readily seen that by moving the plate 52 about the stub shaft 49 the distance between the axes of shaft 42 and stub shaft 53 is changed, thus varying the eccentricity 35 of the stub shaft 53. A frame 54 is pivotally mounted on trunnions 55 secured by set screws 56 in projections 57 on the side walls of the lower section 22 of housing 20. This frame 54 carries an extension 58 which is connected by pivots 58', as shown in Figs. 3 and 8, to a bifurcated link 59 journaled on the stub shaft 53. 40

The frame 54 is provided with a pair of horizontal arms 60 to which the yoke 61 of the link 62 is rockably secured by pivots 61'. A yoke 63 of a link 64 is rockably mounted on another pair of horizontal arms 60' on the frame 54 by pivots 63'. The axes of the two yokes 61 and 63 are parallel to each other and perpendicular to the pivotal axis of the frame 54. A bracket 65 is secured in a second yoke 66 of the link 62 by 50 pivots 65' so that its axis is parallel to the pivotal axis of the yoke 61. Likewise, a bracket 67 is pivotally secured in the second yoke 68 of the link 64 by pivots 67' so that its axis is parallel to the pivotal axis of the yoke 63. A rod 69 is rigidly 55

secured in the brackets 65 and 67, as by set screws or the like, not shown, in such a way that the links 62 and 64 are held substantially parallel.

The mechanism for oscillating the rod 69 longitudinally is best shown in Figs. 3, 4, 10 and 11. A helical gear 70 is fixed on the shaft 42 and meshes with a helical gear 71 fixed on a shaft 72 which is journalled in a bushing 72' fixed by a set screw 73' within a projection 73 on the rear wall, and in a projection 74 on the side wall of the lower section 22 of the housing 20. A yoke 75 is fixed on the end of the shaft 72 by means of a key 76 and a set screw 77 and a stub shaft 78 is journalled in the yoke 75 with its axis parallel to the axis of the shaft 72. The stub shaft 78 can be locked in position by means of a set screw 79 which is threaded transversely through the stub shaft 78 and extends outward through a slot 80 in the yoke 75. A plate 81 is fixedly secured to the stub shaft 78 and carries a stub shaft 82 parallel to the stub shaft 78. An eccentric sleeve 83 carrying a gear 84 is rotatably mounted on the stub shaft 82 and a second sleeve 85 carrying a second gear 86 is rotatably mounted on the sleeve 83. The gears 84 and 86 differ by one tooth and both are engaged by a planetary gear 87 which is rotatably mounted on a shaft 88. The shaft 88 is carried by a plate 89 which is secured to the plate 81 and rotatable on the eccentric sleeve 83. A yoke 90 is pivotally secured at 91 to the sleeve 85 and a rigid link 92, fixed to the yoke 90, is provided at its outer end with a spherical bearing member 93. This bearing member 93 is engaged by two socket members 94 held together by side plates 95 and fixed on the rod 69 by set screws 96. From the foregoing, it can be seen that the extent of oscillation of the rod 69 is controlled by the position of the plate 81 controlling the eccentricity of the stub shaft 82. The yoke 90 holds the sleeve 85 against rotation and the planetary gear 87, rotating with the plate 89, causes the gear 84 and eccentric sleeve 83 to rotate slowly. The oscillation of the rod 69 by means of the stub shafts 53 and 82 is thus varied so that the rod does not always move in the same path.

Two rocker frames 97 and 98 are mounted on the rod 69 for rotation thereabout and two yokes 99 and 100 are pivotally mounted at 101 and 102, respectively, on the frames 97 and 98, respectively. Arms 103 and 104 are secured on the front ends of yokes 99 and 100, respectively, and both arms 103 and 104 extend through an opening 105 in the front wall of the lower section 22 of the housing 20 above the lap 39. An adapter 106 is secured on the free end of the arm 103 by a nut 107 and carries two pins 108 which engage the block 109 carrying the lens 110 and serve to move the lens 110 around and across the lap 39. The use of two pins 108 prevents any rotation or twisting of the block 109 and lens 110 and thus accurately maintains the positioning of the lens 110 relative to the lap 39. An identical adapter 111 is similarly secured on the arm 104.

The mechanisms for imparting pressure to the arms 103 and 104 are identical and only one of these mechanisms will therefore be described. Referring particularly to Figs. 4 and 5, a bracket 112 is fixed in the upper section 21 of the housing 20 by bolts 112' and carries a shaft 113 upon which a tubular lever 114 is pivotally mounted. A bifurcated link 115 is pivotally secured at 115' to the lever 114 and the other end of the link 115 is pivoted on a stub shaft 116 eccentrically mounted on a gear 117. The gear 117 is fixed

on a shaft 118 which is journalled in a projection 119 on the top wall of the upper section 21 of the housing 20 and is held against axial movement by a screw 120. A shaft 121 is journalled in an extension 122 of the upper section 21 of the housing 20 and carries a segmental gear 123 meshing with the gear 117. A crank arm 124 is fixed on the shaft 121 outside the extension 122 for operating the segmental gear 123. A spring 125 is secured at one end to the front wall of the upper section 21 and at its other end to a projection 126 on the link 115. A second projection 127 on the link 115 carries a screw 128 which abuts a stop 129 on the front wall of the upper section 21. The rotation of the gear 117 is thus limited by the screw 128 and stop 129 to a little more than one-half revolution so that the stub shaft 116 is movable between positions above and below the axis of the shaft 118 and in each extreme position, the axis of the stub shaft 116 lies in a plane between the axis of the shaft 118 and the stop 129. The spring 125 holds the gear 117 in its extreme positions.

The tubular lever 114 is open adjacent the shaft 113 and is provided with two upstanding ears 130 and 131 between which a bell crank lever 132 is pivoted on a shaft 133. A threaded rod 134 having a hand grip 135 is threaded in the tubular lever 114 and extends longitudinally thereof to abut the short arm 136 of the bell crank lever 132. The long arm 137 of the bell crank lever 132 has a projection 138 at its free end and a spring 139 connects the projection 138 with a projection 140 on the rear end of the yoke 99. Thus it is apparent that the movement of the crank arm 124 moves the tubular lever 114 between its extreme positions and thus serves to apply or remove the pressure between the lens 110 and the lap 39 while the screw 134 actuates the bell crank lever 132 to tense the spring 139 and thus regulates the amount of pressure between the lens 110 and the lap 39.

In order to lift the arm 103 away from the lens block 109, the tubular lever 114 is provided with an apertured extension 141 within which a rod 142 is slidable. A wing screw 143 serves to lock the rod 142 in position. A link 144 connects the rod 142 and the arm 103 so that when the tubular lever 114 is raised by the crank arm 124, the arm 103 will be lifted away from the lens block 109.

One of the difficulties that has beset the prior art is the protection of the working parts from emery or other abrasive. According to the present invention, the bottom of the lower section 22 of the housing 20 is divided by a low baffle wall 145 which extends across the lower section 22 parallel to the front wall. The rear chamber formed by this wall is an oil reservoir from which oil is pumped over the operating parts in a manner well known in the art. The front chamber formed by the baffle wall 145 is a waste chamber for receiving any emery or other abrasive which may enter the opening 105. A cover plate 146 is secured on the front wall of the lower section 22 of the housing 20 and partially closes the opening 105. Within the housing 20, the yokes 99 and 100, the rocker frame 98 and the yoke 66 are provided with baffle plates 147, 148, 149 and 150, respectively, in alignment with the opening 105 and lying in a plane between the front wall of the housing 20 and the baffle wall 145. Thus any abrasive entering the opening 105 will be deflected by the baffle plates 147, 148, 149 and 150.

into the waste chamber defined by the baffle wall 145.

From the foregoing it will be apparent that we are able to attain the objects of our invention and provide a new and improved lens surfacing machine which is simple in construction yet rugged, efficient and convenient in operation. Various modifications can, of course, be made without departing from the spirit of our invention or the scope of the appended claims.

We claim:

1. In a lens surfacing machine, a housing, a grinding element, a lens holding element, means carried by said housing for moving one of said elements relatively to the other, said means including a lever having means on one end for engaging one of said elements, and a mechanism for urging said elements together, said mechanism comprising an arm mounted within said housing, a crank lever pivotally mounted on said arm, a spring connecting one end of said crank lever to said lever and screw means carried by said arm to actuate said crank lever for varying the tension in said spring.
2. In a lens surfacing machine, a housing, a grinding element, a lens holding element, means carried by said housing for moving one of said elements relatively to the other in continuously changing paths, said means including a lever having means on one end for engaging one of said elements, and a mechanism for urging said elements together, said mechanism comprising an arm pivotally mounted on said housing, means for releasably locking said arm in operative position, a bell crank lever pivotally mounted on said arm, a spring interconnecting said bell crank lever and said lever, and means on said arm for moving said bell crank lever to vary the tension on said spring.
3. In a lens grinding and polishing machine, a housing having an opening in one wall, a grinding element, a lens holding element, means for moving one of said elements relative to the other comprising a frame pivotally mounted in said housing, a second frame pivotally mounted on said first frame with its axis perpendicular to that of the first frame, a lever pivotally mounted on said second frame for movement about axes parallel to the axis of said two frames and having one end extending through said opening, means on said end of said lever for engaging one of said

elements, a spring within said housing and secured to the other end of said lever for causing said lever to press said elements into engagement, means for varying the tension in said spring and means for oscillating said first frame and said second frame about their axes.

4. In a lens surfacing machine, a housing having a front wall and a bottom wall, a baffle wall fixed on said bottom wall substantially parallel to said front wall and serving to define a waste chamber, a grinding element carried by said front wall outside of said housing, a frame oscillatably mounted in said housing, a projection carried by said frame and extending through an opening in said front wall, means on said projection for engaging a lens holding element to move said element across the grinding element, and baffle means carried by said frame between said front wall and said baffle wall opposite said opening whereby abrasives entering said opening will strike said baffle means and fall into said waste chamber.

5. In a lens surfacing machine having a housing, a grinding lap holder comprising a block secured on said housing, a projection on said block for engaging one side of a grinding lap, a key on said block for positioning said lap axially, a jaw, cooperating bearing means on said jaw and on said block, a screw extending through said jaw into said block for moving said jaw on said bearing means, and cooperating shield means on said block and on said jaw for protecting said screw from abrasives.

6. In a lens surfacing machine, a housing having a bottom wall and side walls, a baffle wall extending across said bottom wall adjacent one of said side walls and dividing the lower portion of the housing into an oil chamber and a waste chamber, a grinding element carried outside of said housing adjacent said one of said side walls, an articulated frame reciprocably mounted in said housing, a lens actuating element carried by said frame and extending outside of said housing through an opening in said one of said side walls and baffle plates carried by said frame in alignment with said opening and between said opening and said baffle wall whereby any abrasive entering said opening will be deflected by said baffle plates into said waste chamber.

JOSEPH J. McCABE. 50
GEORGE C. SCHELLING.
